UNITED STATES PATENT OFFICE.

LAWRENCE J. WIDNESS, OF BROOKLYN, NEW YORK.

GARMENT STRETCHER AND PRESSER.

1,270,676.

Specification of Letters Patent. Patented June 25, 1918.

Application filed June 12, 1917. Serial No. 174,231.

To all whom it may concern:

Be it known that I, LAWRENCE J. WIDNESS, a citizen of the United States, and resident of the city of New York, borough of

5 Brooklyn, in the county of Kings and State of New York, have invented a new and Improved Garment Stretcher and Presser, of which the following is a full, clear, and exact description.

10 This invention relates to garment hangers or the like and has particular reference to devices for hanging or treating men's suits or other garments.

15 Among the objects of the invention is to provide a device for holding a pair of trousers in such a manner as to form and maintain creases at the front and back of the legs and to apply sufficient tension or stretch to remove all wrinkles or bagging.

20 Another object of the invention is to provide a garment hanger including a nozzle in the form of an auxiliary bar for supporting an extra pair of trousers as well as a coat and vest.

25 Another object of the invention is to provide a stretcher including a frame with means to adjust the space between the side portions or legs of the frame in accordance with different widths of trousers.

30 With the foregoing and other objects in view the invention consists in the arrangement and combination of parts hereinafter described and claimed, and while the invention is not restricted to the exact details of 35 construction disclosed or suggested herein, still for the purpose of illustrating a practical embodiment thereof reference is had to the accompanying drawings, in which like reference characters designate the same parts 40 in the several views, and in which—

Figure 1 is a front perspective view showing a preferred embodiment of the invention.

Fig. 2 is a vertical sectional detail on the 45 line 2—2 of Fig. 1.

Figs. 3 and 4 are horizontal details on the corresponding lines indicated in Fig. 1.

Fig. 5 is a rear elevation of the upper portion of the device shown in Fig. 1, but 50 with the binding clips loosened; and

Fig. 6 is a simpler modified construction of my invention.

Referring now more particularly to the drawings I show a garment presser and 55 stretcher including a frame having side bars 10 and 11 connected at their upper ends to

a relatively fixed jaw 12 of a clamp whose other jaw is indicated at 13. The upper ends of the bars 10 and 11 are connected to the fixed jaw 12 by means of pivot screws 60 or bolts 14 providing for relative movement of these bars toward and from each other at their lower ends, but said lower ends are held normally spaced from each other to a graduated or predetermined extent by means 65 of a bendable bar 15 having its ends secured to the lower ends of the bars by screws or pivots 16 of any suitable construction, but constituting a permanent connection. By straightening the bar 15 the side bars 10 and 70 11 are forced farther apart, or by bending the bar upwardly to a greater extent the bars are drawn toward each other whereby the distance between the bars may be adjusted to the width of the trousers legs. 75

The relatively fixed and movable jaws 12 and 13 are resiliently connected by means of a hanger hook 17 having two shanks 18 connected to the central portions of the respective jaws. The normal tendency of the 80 bent portion of the hook is to throw the movable jaw forwardly away from the fixed jaw as indicated in dotted lines in Fig. 2. The sliding link 19 operates along the shanks 18 to hold the jaws close together so as to 85 grip the ends of the trousers legs or other garments to be pressed and supported thereby.

Hinged along the outer edges of the relatively fixed bars 10 and 11 are movable bars 90 or wings 20 and 21 which are adapted to swing around the axes of their hinges so as to lie approximately in the same plane as the bars 10 and 11. See the dotted lines in Fig. 4. The hinges for this purpose are 95 indicated at 22 and may be of any suitable construction.

To introduce a pair of trousers into the presser and stretcher the device is laid down flat on its back and the wings 20 and 21 are 100 thrown open and the link 19 is slipped up onto the hook 17 so as to release the movable jaw 13. The ends of the trousers legs are then put squarely together and inserted between the movable jaws 12 and 13 with the 105 edges or creases of the legs laid flat upon the fixed bars 10 and 11, the edges of the trousers legs being moistened somewhat to facilitate the creasing and pressing action. The clamp is then closed snugly upon the ends 110 of the trousers by slipping the link 19 down the shanks 18. With the ends of the trousers

legs thus clamped, the operator will draw downwardly with sufficient force upon the trousers to put them under proper tension lengthwise and then swing the movable bars 5 or wings 20 and 21 in succession over upon the creased portions thereof. These movable wings are then clamped in closed position by means of suitable devices such as spring clips 23 each carried by a flexible loop 24 upon 10 the adjacent bar 10 or 11 and having sufficient flexibility to slip readily over both of the adjacent bars and also enough strength to hold the bars tightly upon those portions of the trousers legs to be creased.

15 The free ends of each clip are preferably bent away from each other to facilitate the attachment of the clips to binding position. After the wings are thus closed and locked by means of the clips 23, a spreader bar 25 20 having fixed connection at 26 with the wing 20 is put in place, its free end being forced upwardly beneath an undercut edge of the cleat 27 carried by the wing 21. The connected end 26 is adapted to bear against a 25 fixed abutment 28 to give sufficient resistance to the spreader. The action of this bar 25 is twofold: First, it serves to coöperate with the bar 15 to spread the free ends of the frame and it also coöperates with the cleat 23 to 30 hold the wings against or toward the bars 10 and 11 and in the same plane. The bar 25 is longer than the shortest distance between the abutment and cleat and hence when the free end of the bar is forced beneath the cleat the 35 bar acts to force the leg portions of the frame apart and also insures that the bar will remain in place by frictional contact of the cleat. It will thus be seen that the trousers will not only be pressed and creased but will 40 be stretched both longitudinally and laterally to remove all wrinkles and bagging.

I now refer to the auxiliary garment support shown in Figs. 1 and 6, the same comprising a transverse bar 29 having loops 30 45 bent parallel to the main portion of the bar and extending thence downward parallel to each other at 31 and connected preferably to the bolts 14. The main bar 29 is thus arranged in a vertical plane to the rear of the 50 main plane of the hanger and the plane of the parallel portions 31. This bar 29 serves immediately as a support for an extra pair of trousers hung upon the same in folded position, and the loops 30 serve to support a 55 coat and vest or other similar garment. It is obvious that this device in substantially the same form as that illustrated may be made

in larger or smaller sizes to adapt it for pressing or stretching ties, scarfs, and any other desired garments. Furthermore the 60 device is of a relatively cheap and simple construction and is one adapted for easy and rapid manipulation for the purposes indicated.

I claim:

1. A garment presser and stretcher comprising side bars, wings hinged to the side bars and having their upper ends terminating short of the upper ends of the said bars, means for locking the wings closed, two 70 parallel cross bars, said cross bars being on opposite sides of the upper ends of the side bars and to one of which the said upper ends of the side bars are pivoted, a hanger hook having integral resilient shanks secured to 75 the cross bars and normally holding the bars away from each other, a link slidable on the shanks of the hanger hook and serving to hold the said bars close together, the bars, hanger and link forming a clamp, and 80 means for spreading the lower ends of the side bars.

2. In a garment presser and stretcher, side bars, a clamp at the upper end of the side bars and to one member of which the upper 85 ends of the side bars are pivoted, wings hinged to the side bars, flexible loops mounted on the side bars, and spring clips carried by the said loops for clamping the wings in closed position, the free ends of the clips 90 being bent to form handles to facilitate operating them.

3. The herein described garment presser and stretcher comprising a pair of side bars, a clamp, to one member of which the upper 95 ends of the side bars are pivoted, a pair of wings, one for each bar, a plurality of hinges connecting the outer edges of respective pairs of bars and wings providing for the movement of each wing around a longitudinal 100 axis into substantially the same plane as its bar to introduce a garment, a plurality of spring clips carried by each bar and adapted to flexibly embrace such bar and its wing when the wing is in closed position, a bendable bar connecting the lower ends of the side bars and serving to determine the normal distance between them, an undercut cleat on one wing, and a rigid spreader bar secured to one wing and engaging the said cleat when 110 the wings are in closed position to place the same under transverse tension.

LAWRENCE J. WIDNESS.
